Primary Examiner — Paul D Bohannon(74) *Attorney, Agent, or Firm* — McHale & Slavin, P.A.(57) **CLAIM**

The ornamental design for a chair as shown and described.

DESCRIPTION

FIG. 1 is a top front left perspective view of the chair of the present invention;

FIG. 2 is a top rear right view thereof;

FIG. 3 is a right side view thereof;

FIG. 4 is a left side view thereof;

FIG. 5 is a front view thereof;

FIG. 6 is a rear view thereof; and,

FIG. 7 is a top view thereof.

The broken lines showing portions of the chair form no part of the claimed design.

1 Claim, 7 Drawing Sheets(56)
